(57) **CLAIM**

The ornamental design for a charger for cellular phone, as shown and described.

DESCRIPTION

FIG. 1 is a front, left side, perspective view of a charger for cellular phone showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof, shown in an open position; and,

FIG. 9 is a left side view thereof, shown in an open position. The broken lines shown in the drawings are included for the purpose of illustrating environmental structure and form no part of the claimed design.
